PAPER-FEED FOR AUTOGRAPHIC REGISTERS.

1,816,581.

Specification of Letters Patent. Patented Sept. 23, 1919.

Application filed May 27, 1919. Serial No. 300,141.

To all whom it may concern:

Be it known that we, HARRY H. KONERMAN and ROBERT C. LEIMBERGER, citizens of the United States of America, and residents 5 of Newport and Cincinnati, in the counties of Campbell and Hamilton and States of Kentucky and Ohio, have invented a new and useful Improvement in Paper-Feeds for Autographic Registers, of which the following is a specification.

Our invention relates to paper feeders which are actuated by the turning of a crank. The object of our invention is improved means for automatically rendering 15 the crank inoperative for feeding paper after a certain length of paper has been fed out of the register.

This object is attained by the means described in the specification and illustrated 20 in the accompanying drawing, in which:—

Figure 1, is a plane view of the front end of an autographic register supplied with a paper feeder embodying our invention.

Fig. 2, is a sectional view taken upon line 25 2—2 of Fig. 1.

Fig. 3, is a detail view partly in section and partly in elevation of one of the rotatable contact members which coöperate with the feed rolls.

Fig. 4, is a view of the details of the feed shaft and means for causing it to rotate in one direction.

Referring to the parts:

The autographic register upon which we have illustrated our feeder as being attached 35 has the usual casing A within which the rolls of paper are mounted and has at its forward end the usual writing plate, which is placed at the front of the machine so as to register with the opening a in the hinged top A', the hinges of which are at the rear end, not shown, of the register. Upon one side of the casing A is mounted a carbon paper roll A². All of these parts are of 40 well known construction and need not therefore be more specifically described.

In the front walls of the casing is journaled feed shaft B upon which are mounted feed rolls b, b'. The feed shaft carries at 50 one end a ratchet wheel b² which is engaged by pawl b³ which permits rotation of the shaft only in a forward direction. Feed rolls b, b' project through slots a, a' in the top of the front plate A³ of the casing, so

that the periphery of the feed rolls, in their 55 rotation, is flush with the upper face of the plate A³.

Mounted vertically above the shaft B, is a support bar D, which is mounted upon standards d, d' which are secured to the 60 sides of the casing by means of screws d², d³. Standards d, d' have inwardly projecting sides d⁴ between which the reduced ends of the support bar D are mounted upon pins d⁵, d⁶, which are made removable.

Support bar D has mounted reciprocably upon it a shift bar E which carries journal boxes e, e' for rotatable contact members, which preferably consists of metallic balls e², e³. The journal boxes e, e' are mounted 70 upon the shift bar E in position such that in its normal position the contact devices e², e³ are in central alinement with the feed rolls b, b'.

To permit reciprocation of the shift bar 75 E upon the support bar D, the shift bar is mounted upon the support bar by large headed screws e⁴, e⁵, the shanks of which pass through longitudinal slots e⁶, e⁷, in the shift bar, which has a central slot in which 80 is located a spring e⁸ which at one end is secured to the bar E and at the other end to the bar D, and is adapted to hold the end of the slots e⁶, e⁷ in contact with the screws e⁴, e⁵, in which position of these parts the 85 balls e², e³ are in alinement with the feed rolls b, b'. To enable the operator to shift the bar E there is a knob F whose shank projects through a slot d⁹ in the support bar D and slot g in the housing G. Housing G 90 is mounted upon the casing by having its sides slotted to pass over the enlargements upon the shanks of the screws d², d³.

The journal boxes e, e' are in the form of cylindrical cups which have at one end ball 95 bearings e⁹. The balls e², e³ are of the diameter of the cups.

Each web of paper H, H' has in it two series of alined holes, each series being spaced transversely a distance apart equal 100 to the distance between the balls e², e³. The longitudinal distance between the holes in a series may be varied according to the length of paper that it is desired to have in each ticket, that is to be severed by the 105 cutting edge A⁴ of the register.

In use the webs H, H', from the rolls of paper, having had the holes in them regis-

tered, are passed over the front plate A³ and between the feed rolls b, b' and the balls e², e³, in position such that the series of holes in the webs are in alinement with the 5 balls e², e³, which will hold the webs in contact with the feed rolls b, b' until such time as the holes in the paper register with the balls e², e³.

A rotation of the feed shaft will cause 10 the paper to be fed forward until the balls register with the holes in the paper, in which position further rotation of the feed shaft is ineffective for feeding the paper. To feed the paper forward it is then necessary to 15 shift the shift bar E to one side so as to draw the balls out of the holes in the paper and to cause them to hold the paper in contact with the feed rolls at the peripheries of the holes in the paper. Rotation of the shaft 20 will then feed the paper forward. Thereupon the operator releases knob F and the spring e⁸ returns the balls to their normal position in alinement with the series of holes. Rotation of the crank then will con- 25 tinue to feed the sheets of paper forward until the balls register with the next holes in the paper.

Having thus described our invention, what we claim is:—

30 1. In a paper feed for autographic registers the combination of feed rolls, rotatable contact members, means for mounting the contact members so that they may be held in a normal position in contact with the feed 35 rolls and may be shifted to one side of the normal position.

2. In a paper feed for autographic registers the combination of feed rolls, a shift bar, means for mounting the shift bar ad- 40 jacent to the feed rolls and a rotatable contact device mounted upon the shift bar in contact with the feed rolls.

3. In a paper feed for autographic registers the combination of a feed roll, a shift

bar, means for mounting the shift bar ad- 45 jacent to the feed roll, a journal box mounted upon the shift bar in alinement with the feed roll, and a ball mounted in the journal box and adapted to contact with the feed roll. 50

4. The combination of a casing of an auto- graphic register, a feed shaft mounted in the forward end of the casing, feed rolls secured upon the feed shaft, a support bar secured upon the casing in alinement with 55 the feed shaft, a shift bar mounted recipro- cally upon the support bar, and rotatable contact devices mounted upon the shift bar in alinement with the feed rolls.

5. The combination of a casing of an auto- graphic register, a feed shaft mounted in the forward end of the casing, feed rolls se- 60 cured upon the feed shaft, a support bar secured upon the casing in alinement with the feed shaft, a shift bar mounted recipro- cally upon the support bar, journal boxes secured upon the shift bar in alinement with 65 the feed rolls and balls mounted in the jour- nal boxes and adapted to contact with the feed rolls. 70

6. The combination of a casing of an auto- graphic register, a feed shaft mounted in the forward end of the casing, feed rolls se- 75 cured upon the feed shaft, a support bar secured upon the casing in alinement with the feed shaft, a shift bar mounted recipro- cally upon the support bar, journal boxes mounted upon the shift bar in alinement 80 with the feed rolls, ball bearings in the top of the journal boxes and contact balls mounted in the journal boxes and adapted to contact with the ball bearings and with the feed rolls. 85

In testimony whereof, we have hereunto subscribed our names this 26th day of May, 1919.

HARRY H. KONERMAN.
ROBERT C. LEIMBERGER.
